UNITED STATES PATENT OFFICE.

GEORGE J. GOODHUE, OF STEVENS POINT, WISCONSIN, ASSIGNOR OF ONE-THIRD TO HARVEY M. WADLEIGH, OF SAME PLACE.

ENGINE-STARTER.

SPECIFICATION forming part of Letters Patent No. 332,197, dated December 8, 1885.

Application filed August 4, 1885. Serial No. 173,508. (No model.)

To all whom it may concern:

Be it known that I, GEORGE J. GOODHUE, of Stevens Point, in the county of Portage, and in the State of Wisconsin, have invented 5 certain new and useful Improvements in Engine-Starters; and I do hereby declare that the following is a full, clear, and exact description thereof.

My invention relates to devices for starting 10 the fly-wheel of a stationary engine when the crank of the connecting-rod has stopped on a center, or for moving the wheel for any purpose; and it consists in certain peculiarities of construction, as will be more fully set forth 15 hereinafter.

In the drawings, Figure 1 is a perspective view of the fly-wheel of an engine with one form of my device applied thereto in position to move said wheel off the dead-center. Fig. 20 2 is a plan view of another form of my device applied to the rim of a wheel, the latter being shown in section. Fig. 3 is a detail sectional view of the form of starter shown in Fig. 1, but with the cam shown against the outer 25 periphery of the wheel. Fig. 4 is a detail of still another form, illustrating the extension-yoke; and Fig. 5 is a detail of the gripping-cam.

Heretofore in many instances the periphery 30 of the fly-wheel has been cast with a series of holes at given distances apart, so that when the said wheel stopped on a center, or when, for any reason, it was necessary to move said wheel, as when the steam is off, this could be done by inserting a rod in one of said holes and turning the wheel thereby; but this is 35 awkward and requires a great expenditure of strength and the efforts of a number of men, and when the periphery of the wheel is smooth 40 still greater force and labor are required, and when there is a little steam left in the cylinder the operation is attended with considerable danger.

The object of my invention is to obviate all 45 this, and to provide a simple, easy, and efficacious means for turning the said fly-wheel when required.

A represents the fly-wheel of a stationary engine; B, its shaft; C, the crank, and D the 50 connecting-rod. E is a fulcrum, of any ordinary construction, as shown, for supporting

my device, which latter consists of the socket F, having lever G inserted in its open rear end, and with a ball, H, in its partly-closed front end, the under side of said front end being 55 slotted, as shown at F', to accommodate the shank h of said ball, which terminates in another ball, H', squared at its sides and perforated to receive the bolt i', forming what is known as a "union-ball" connection with the gripping-cam, to be next described. The inner surface of the front end of the socket F is of course rounded, as shown, to correspond with the ball H.

The gripping-cam I (shown in detail in Fig. 65 5) has a short shank, i, and a bifurcated end, I', and the part H' of the union-ball is inserted between the forks of this end and secured therein by the bolt i', which passes through perforations in said parts H' and I', so that 60 there will be plenty of room for free play on said bolt i', as shown in Fig. 3. The operative end of said cam I is ground flat in a series of transverse bearing-faces, i² i², each about half an inch wide, which gives a greater 75 degree of pressure or grip against the smooth periphery or the side of the rim of the wheel A, and the other end of said cam is provided with a transverse perforation, i³, to receive a shoulder-bolt, k, the said perforation i³ and 80 that part of the bolt k which rests within it being each perfectly round and smooth, while beyond this point the bolt k is screw-threaded and tapped into a screw-threaded perforation in the yoke K, so that the cam I is practically 85 pivoted on the bolt k and can swing freely thereon. The yoke K is formed with an end extension, K', (cast solidly therewith in the forms shown in Figs. 1, 2, and 3,) and this part K' (which is at a right angle to the length 90 of the yoke proper) is transversely perforated to receive a screw, L, for the purpose of adjusting the yoke to different widths of wheel-rims, the said bolt being fitted with a set-nut, l, so that it will remain stationary after adjustment.

In Figs. 1 and 3 I have shown the simplest form of my device, adapted especially for narrow-rimmed wheels, and in these forms the yoke is solid with its extension. In Fig. 2 100 I also show a solid yoke, but have added (for wheels having wider rims) the guard M, con-

sisting of an angle-piece of iron of the shape shown, which is perforated to receive the screw L , and which has also another perforation to receive a tap-screw, N , passing also into a threaded perforation in the yoke end K' , for greater security, the guard M ending in an inward projection, m , which bears against the inner surface of the wheel-periphery and prevents the said part from slipping away from position, as might happen with wide-rimmed wheels with the form of device shown in Fig. 1.

In Fig. 4 I have made still further provision for very wide rimmed wheels, wherein I have illustrated the extension K' as being constructed with a sleeve which slides upon the long arm of the yoke K , so as to be adjusted to any distance required, the said sliding extension K' being secured in the desired adjustment by holes k' in the part K , and pins k'' , passing through these holes and corresponding holes in the part K' , as shown in full lines, or by a set-screw, k^3 , as shown in dotted lines in said Fig. 4, or by any equivalent fastening device, as desired. In this form, I usually make the long bar of the yoke of wrought-iron or steel, and instead of using the described shoulder-bolt k , I may bend the end of the said long bar around (suitably reduced and rounded of course) so as to form a pivot, k , for attachment to the cam I , as an equivalent for the bolt k , and secure the cam I to place thereon by a pin, as shown.

The operation of my device will be readily understood from the foregoing description of its construction. When it is desired to start the wheel A , the parts being, for instance, in the relative position, shown in Fig. 1, the socket F is rested on the fulcrum E , and the yoke and cam placed against the wheel-rim, as shown. Now, by raising the outer end of the lever G the yoke will slide down on the wheel-rim, (the cam I moving upward enough to permit this movement,) and then the bearing-faces i^2 of the cam will tightly grip against the side of the rim of said wheel, (holding the same tightly between the cam and the screw L ,) and as the lever G is depressed the wheel will be turned. The "ball-union" H h H' and the slot I' in the socket F enable the parts to have free play and accommodate themselves to the different distances between the point of contact of the cam, &c., as the wheel and the fulcrum-point of said socket on the wheel is turned, so that the fulcrum does not

need to be moved if more than one movement 55 has to be given to the wheel.

It will be seen that my device is equally well adapted to bear against the sides of the wheel-rim as it is against the outer and inner peripheries thereof, and either form shown 60 may be modified in this respect and made adjustable either way, without departing from the spirit of my invention.

If desired, other forms of connection than the union-ball shown may be employed to 65 unite the lever and cam; but it is desirable that a yielding connection be employed, for obvious reasons.

Having thus described my invention, what I claim as new, and desire to secure by Letters 70 Patent, is—

1. An engine-starter consisting of a lever and socket and a bearing-cam with a yielding connection, and a yoke pivoted to said cam and provided with an adjustable screw for 75 gripping the rim of the fly-wheel of the engine between said cam and the screw of the yoke, substantially as set forth.

2. In an engine-starter, the combination of 80 the lever and socket and bearing-cam, connected by a union-ball with a yoke pivoted to said cam, and having an extension provided with an adjustable screw, and a guard adapted to bear against the inner periphery of the fly-wheel of the engine, substantially as 85 set forth.

3. In an engine-starter, the combination of 90 the lever and socket and bearing-cam, connected by a union ball with a yoke pivoted to said cam, and having a sliding extension secured thereto, provided with an adjustable screw and a rim guard, substantially as set forth.

4. An engine-starter consisting of a lever and bearing-cam, united by a yielding connection, in combination with a yoke pivoted to 95 said cam and adapted to bear against the rim of a wheel on the side opposite to that surface which comes in contact with the cam, substantially as set forth.

In testimony that I claim the foregoing I have hereunto set my hand, at Milwaukee, in the county of Milwaukee and State of Wisconsin, in the presence of two witnesses.

GEORGE J. GOODHUE.
